UNITED STATES PATENT OFFICE

ROBERT T. ROMINE, OF MOUNT CLEMENS, MICHIGAN

APPARATUS AND METHOD FOR SHIPPING METAL

Original applications filed September 10, 1927, Serial No. 218,791, now Patent No. 1,745,054, dated January 28, 1930, and filed October 20, 1928, Serial No. 313,846, now Patent No. 1,745,057, dated January 28, 1930. Divided and this application filed January 28, 1930. Serial No. 422,847.

This invention relates to a method and apparatus for binding and shipping sheet metal in compact unitary packs or bundles on the floor of freight cars or carriers. Large quantities of sheet metal or sheet steel are shipped from steel or rolling mills to automobile manufacturers and others, and an object of the invention is to provide a method and apparatus whereby packs or bundles of this metal containing groups of sheets of different sizes may be formed and shipped in an efficient and economical manner.

This application is a division of my Patents Nos. 1,745,054, granted January 28, 1930, and 1,745,057, granted January 28, 1930.

Other objects of the invention will appear in the following description and appended claims reference being had to the accompanying drawings forming a part of this specification wherein like reference characters designate corresponding parts in the several views.

In said drawings:

Fig. 1 is a side elevation of a bound pack or bundle of metal embodying the invention.

Fig. 2 is an end elevation of the construction shown in Fig. 1.

Fig. 3 is an end elevation of a modified form of bound pack or bundle.

Fig. 4 is a side elevation of the pack shown in Fig. 3.

Before explaining in detail the present invention it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto appended or the requirements of the prior art.

In Figs. 1 and 2 of the drawings I have shown at S a bound pack or bundle wherein two groups of metal sheets of different sizes are bound together for shipment, the pack as a whole being supported with the sheets dis-

posed on edge upon transverse riding blocks or pallet members P.

The pack S is formed of metal sheets of mixed or different sizes, including in this instance one group A of relatively narrow sheets and another group B of wider sheets, which groups are bound together in a suitable manner so as to maintain them in position with respect to each other. By way of illustration the pack may be bound by means of binders shown as a whole at D, which type of binder is shown and described in my Patent No. 1,650,540, dated November 22, 1927, and which type I have shown by preference since greater strength and pressure against the sheet edges is possible.

Each of the binders comprises four angular sections, d, d¹, d² and d³, each consisting of a pair of similarly formed parallel metal bars 10. The ends of the binder sections overlap 70 and are preferably secured together by means of bolts and spacing devices 11. Each of the members 10 is provided with a plurality of holes 10a adapted to receive the bolts 11 and to permit adjustability of the binder.

At the top of the pack S I position wood blocks or filler strips which are adapted to cooperate with the binders D encircling the pack. Above the section A of the pack I place several bars or blocks of wood F so as to 80 compensate for the space between the upper edges of the sheets forming the portion A and the upper edges of the sheets of the portion B of the pack. Above the portion B I provide preferably a wood bar or block F. 85 Beneath the pack at the point where each binder underlies the bottom edges of the sheets of the pack, and upon the binder D at that point, I preferably place a wood strip or bar F2 for the purpose of protecting the 90 lower edges of the sheets when the binder which underlies the pack at that point is drawn into position to firmly bind the sheets together into a compact unit. The yoke frame D of the binder is shown as carrying a number of pressure devices E, which are substantially like those shown and described in my above mentioned patent and serve to tighten the binder by exerting inward pressure against the pack of metal. In using this type 100

binder, after the pressure devices have been placed in position they are preliminarily tightened to draw the bottom part of the yoke frame upwardly toward the lower edges of the sheets and grip the wood bar or strip F2 therebetween. As shown in Fig. 1, with packs of metal of normal size I preferably employ two binders D, these being positioned preferably adjacent each end of the pack.

10 After each of the binders have been drawn upwardly so as to grip the wood members F2 against the lower edges of the pack, longitudinal wood members or bars F3 may be interposed between the pressure devices and the pack at opposite vertical sides of the latter, and by tightening the devices E through the medium of their adjusting screws E', considerable pressure is possible so as to compress and maintain the constituent sheets of both portions of the pack together as a unit or single mass. Additional pressure may be applied to the adjusting screws E' of the pressure devices at the top of the pack, whereupon the sheets are firmly held together as a unit.

25 At opposite longitudinal sides of the pack longitudinal wood members or bars H are mounted on the riding or skid members P, these bars being provided adjacent opposite ends with notches or cutout portions H', formed in the wood members at the points where the binders D encircle the pack. The binders extend into these notches thereby interlocking the parts together. These members H are secured to the riding blocks or pallet members F by means of nails or the like 12 (Fig. 1) and act to hold the pallet or skid members P together as well as to hold the pack and pallet members together as a unit.

40 It will be understood that the packs may be formed at any convenient point, preferably at the final operation at a steel mill. When the packs are to be shipped in freight cars and bound by means of binders as above illustrated, the riding blocks or pallet members P are positioned transversely upon the car floor at spaced intervals so as to permit the binders D of the pack to be positioned between adjacent riding blocks free from contact with the car floor. It will be noted that the blocks P are thicker than the thickness or transverse diameter of the binders D so that when the pack is supported upon the pallet members the binders are out of contact with the car floor (see Fig. 1). When a pack is placed in a carrier for shipment it merely rests upon the floor thereof and is not secured thereto but on the other hand is permitted to float or move on the carrier floor during transit. 55 In order to prevent any accidental lateral or sidewise movement of the pack when shifting on the car floor as a result of shocks during transit, guide blocks G are preferably positioned at opposite ends of the pallet mem-

bers P longitudinally of the car and are secured to the car floor.

In Figs. 3 and 4 I have shown the invention as applied in connection with packs of sheet metal wherein the sheets are of different sizes and are positioned flatwise. In this form of the invention the riding blocks P are similarly employed to support the pack S' in position upon a carrier floor for shipment, and the pack containing sections of different size sheets is illustrated as bound together by means of binders D' similar to those shown in Figs. 1 and 2.

75 Referring to Figs. 3 and 4, the entire pack made up of sections C, A' and B' of different size sheets or strips, may be supported on the car floor upon riding or skid members P which in this instance are tied together for unitary movement on the car floor such as by means of longitudinal angles 15 having 80 spurs or projections 15' capable of frictionally holding the riding members together by embedding therein.

90 The particular pack shown in Fig. 3 is formed by piling the wider metal sheets C within the angles 15 upon riding or skid members, after which one group A' of narrower metal sheets or strips are piled upon the top of the sheets C. Although these sheets A' are shown as piled directly on the sheets C, they may be separated by spacers if desired. Wood filler members or bars I are placed in position against the inner edges of the sheets A', and thereupon another group 95 of sheets B' are stacked on top of the sheets C with their inner edges abutting against the filler members I. The entire mass is then 100 bound together by suitable means capable of maintaining the different size sheets in proper position with respect to each other. Tight binders are important in pressing the 105 wood filler members against the edges of the shorter sheets while at the same time exerting substantially equivalent pressure against the wider sheets, or another group of sheets 110 of the same pack.

115 The rigid binders D' carrying pressure devices E are illustrated in Figs. 3 and 4 by way of example, this type of binder having the advantage of greater strength and pressure capacity. The invention however is not limited to the binder herein shown. The application of the binders herein illustrated is as follows: the binders D' comprising four sections are placed about the entire pack S'. A pair of wood members or bars K, one for each binder D' is then placed upon the top of the portions A' and B' of the pack between those portions and the binders. Pressure devices E are then inserted between the binders and the wood members K and preliminarily tightened to draw the bottom parts of the binders into engagement with the angles 15 at the under side of the pack. A similar bar L is also placed against the left vertical side of 120 125 130

the pack, it being understood that a pair of such bars are provided for each binder. Pressure devices E are then inserted between the bars L at the left side of the pack and the binder sections at that point, these being tightened through the medium of their adjusting screws to draw the binder sections at the right side of the pack into engagement with the wood members L positioned at that side so as to clamp such members between the binders and the edges of the sheets at that side of the pack. Final pressure may then be applied to the pressure devices E at the top of the pack. Likewise final pressure may then be applied to the pressure devices at the left side of the pack whereupon the sheets of the several groups or packs A', B' and C will be pressed together to form a compact unitary bundle.

The wood members L at the vertical sides of the pack may be cut away or notched at their lower inner faces where they engage the vertical flanges of the angles 15. These wood members, however, may be formed of relatively soft wood and hence it would not be necessary to provide such notches, since upon applying pressure to the binders the angles will be forced into the wood members.

From the foregoing it will be seen that the pack or bundle and the pallet or skid members will move together as a unit when the carrier in which they are being shipped is subjected to shocks, blows or impacts during transit. That is to say, the pack of Figs. 3 and 4 is allowed to have a slight relative movement or floating action upon the car floor during shipment. It will be also understood that when the pack S' is placed in a carrier for shipment, the usual guide members G are nailed to the car floor to prevent lateral or sidewise movement of the packs during shipment.

From the foregoing it will be seen that I have provided a method and apparatus whereby heavy bundles of metal containing groups or packs of sheets of different sizes may be bound into unitary bundles for shipment in carriers, and at destination may be removed as units from the car.

While I have shown merely for purposes of illustration two forms of bundles containing sheets of different sizes various other forms of bundles containing groups or packs of sheets of different sizes may be formed in accordance with the invention.

I may employ, if desirable, a single wood member to take the place of the wood members or blocks F of the pack shown in Figs. 1 and 2. Likewise I may find it desirable to employ several wood members or bars in lieu of the wood member I forming a part of the pack shown in Figs. 3 and 4.

From the foregoing it will be seen that sheets of different widths may be stacked in packs and all bound together as a unit,

equal pressure being exerted against the edges of the wider and narrow groups or packs of sheets whereby irrespective of the different sizes of sheets all of them will be firmly held together as a single mass unit during transit against relative displacement.

I claim:

1. The herein-described method of transporting sheet metal flatwise on the floor of a freight car, consisting in arranging sheets of different widths to form a single pack, with the sheets of one width on top of the sheets of another width, and binding the pack to exert substantially equal pressure on the wider and narrower portions of the pack to maintain the pack as a unit.

2. The herein-described method of transporting sheet metal flatwise on the floor of a freight car consisting in arranging sheets of different widths one on top of another to form a single pack, and binding the pack to exert substantially equal but independently exerted pressure on the wider and narrower portions of the pack to maintain the pack as a unit.

3. The herein-described method of transporting sheet metal flatwise on the floor of a freight car, consisting in arranging sheets of different widths as units one on top of another to form a single pack, and binding the pack and exerting substantially independently pressure on the edges of the wider and narrower units of the pack to maintain the pack as a unit.

4. Apparatus for binding sheet metal flatwise in a pack or bundle on a freight car floor for transportation in which the bundle comprises a plurality of portions of different widths comprising a binder encircling the pack, and means cooperating with said binder for maintaining the narrower portion of the pack in position relative to the wider portion, said means including a wooden filler in the pack area beside the narrower sheets and in the same vertical plane as the wider sheets.

5. Apparatus for binding sheet metal flatwise in a pack or bundle on a freight car floor for transportation in which the bundle comprises a plurality of portions of different widths comprising a binder encircling the pack, angle bars supporting opposite longitudinal side edges of the pack, and means cooperating with said binder and angle bars for maintaining the narrower portion of the pack in position relative to the wider portion, said means including a wooden filler within the pack area beside the narrower sheets but above and on the wider sheets.

6. Apparatus for binding sheet metal flatwise in a pack or bundle on a freight car floor for transportation in which the bundle comprises a plurality of portions of different widths comprising a binder encircling

the pack, filler blocks interposed between the pack and the binder and arranged on the wider sheets but beside the edges of the narrower sheets, and pressure devices carried by said binder for maintaining the narrower portion of the pack in position relative to the wider portion.

7. Apparatus for binding sheet metal flatwise in a pack or bundle on a freight car floor for transportation with the sheets resting flatwise in which the bundle comprises a plurality of portions of different widths resting as units one on top of the other comprising a binder encircling the pack, and means cooperating with said binder for exerting substantially equal pressure against the edges of the sheets of the wider and narrower portions of the pack.

8. Apparatus for binding sheet metal flatwise in a pack or bundle on a freight car floor for transportation with the sheets resting flatwise in which the bundle comprises a plurality of portions of different widths, comprising a binder encircling the pack, means cooperating with said binder for maintaining the narrower portion of the pack in position relative to the wider portions, and means for exerting pressure against said last means.

20 9. Apparatus for binding sheet metal flatwise in a pack or bundle on a freight car floor for transportation with the sheets resting flatwise in which the bundle comprises a plurality of portions of different widths comprising a binder encircling the pack, wood members engaging the narrower portion of the pack, and pressure devices between said binder and pack for maintaining the narrower portion of the pack in position relative 25 to the wider portion.

40 10. Apparatus for binding sheet metal flatwise in a pack or bundle on a carrier floor for transportation in which the bundle comprises a plurality of groups of metal sheets of different widths arranged one above the other, comprising wood filler means facing the edges of the shorter group of sheets and engaging the faces of wider sheets and in the vertical planes of the latter, binding 45 means pressing said groups of sheets and said wood filler means together to maintain the sheets in position with respect to each other, and supporting means for the pack free to shift with said pack as a unit relatively to 50 the car floor.

55 11. The method of transporting sheet metal flatwise on the floor of a freight car or carrier comprising arranging groups of sheets of different widths to form a single pack, binding the pack to maintain the groups of sheets in substantially fixed relative positions in the pack, and allowing the groups of sheets to shift or float flatwise as a unit relatively to the car floor when the car 60 is subjected to shocks or blows.

12. The method of transporting sheet metal flatwise on the floor of a freight car or carrier comprising arranging groups of sheets of different widths to form a single pack, binding the pack to maintain the groups of sheets in substantially fixed relative positions, supporting the groups of sheets as a unit by means interposed therebetween and the car floor, and allowing the groups of sheets to shift or float flatwise as a unit relatively to the car floor during transit.

70 13. The method of transporting sheet metal flatwise on the floor of a freight car comprising arranging groups of sheets of different widths to form a single pack, binding the pack to maintain the groups of sheets together in the pack, allowing the groups of sheets to shift or float flatwise as a unit longitudinally of the car floor during transit, and guiding the pack to predetermine its longitudinal movement.

75 14. The method of transporting sheet metal flatwise on the floor of a freight car comprising arranging groups of sheets of different widths to form a single pack, binding the pack to maintain the groups of sheets together in the pack, supporting the groups of sheets flatwise as a unit on riding members to permit the groups to shift or float as a unit longitudinally of the car during transit thereby to resist relative shifting of the sheets of the groups.

80 In testimony whereof I have hereunto set my hand.

100 ROBERT T. ROMINE.
